Primary Examiner — Kevin K Rudzinski

Assistant Examiner — Kathleen L Jones

(74) Attorney, Agent, or Firm — Davis Wright Tremaine
LLP(57) **CLAIM**The ornamental design for a passive multiplexer, as shown
and described.

DESCRIPTION

FIG. 1 is a perspective view of a passive multiplexer
showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings are for purposes of
illustrating portions of the passive multiplexer that form no
part of the claimed design.**1 Claim, 7 Drawing Sheets**(56)
